(57) **CLAIM**

The ornamental design for a slide out double bulb seal, as shown and described.

DESCRIPTION

FIG. 1 is a perspective view of a slide out double bulb seal, in accordance with the present invention;

FIG. 2 is a front elevation view of the slide out double bulb seal, in accordance with the present invention;

FIG. 3 is a rear elevation view of the slide out double bulb seal, in accordance with the present invention;

FIG. 4 is a right side elevation view of the slide out double bulb seal, in accordance with the present invention;

FIG. 5 is a left side elevation view of the slide out double bulb seal, in accordance with the present invention;

FIG. 6 is a top plan view of the slide out double bulb seal, in accordance with the present invention; and, FIG. 7 is a bottom plan view of the slide out double bulb seal, in accordance with the present invention.

The evenly spaced broken lines depict a symbolic break in the article. The portion between the break lines forms no part of the claimed design.

1 Claim, 7 Drawing Sheets
